UNITED STATES PATENT OFFICE.

MARTIN L. SCHOCH, OF NEW BERLIN, PENNSYLVANIA.

THILL-COUPING.

SPECIFICATION forming part of Letters Patent No. 423,634, dated March 18, 1890.

Application filed January 22, 1890. Serial No. 337,711. (No model.)

To all whom it may concern:

Be it known that I, MARTIN L. SCHOCH, of New Berlin, in the county of Union and State of Pennsylvania, have invented a new and Improved Thill-Coupling, of which the following is a full, clear, and exact description. My invention relates to improvements in couplings for attaching shafts and tongues to a vehicle-axle; and the object of my invention is to provide a coupling of few parts that will be strong, durable, and cheap, that can be easily applied to a vehicle, that will hold the parts securely together, and by means of which the parts may be quickly and easily coupled or uncoupled.

To this end my invention consists of two forwardly-projecting lugs or ears attached to the axle-clip in the usual way and provided with a cross bolt or shaft, a slotted thill-iron having its terminal end formed into hooks to engage said cross-bolt and a raised knuckle near the end of the thill, and a peculiarly-formed key adapted to enter the slot of the thill-iron, engage the knuckle thereon, and overlap the cross-bolt, thus holding the parts together, said key being provided with a depending lever by which it may be locked in position. This construction will be herein-after fully described, and specifically pointed out in the claims.

Reference is to be had to the accompanying drawings, forming a part of this specification, in which similar letters of reference indicate corresponding parts in all the figures.

Figure 1 is a plan view of the device applied to a thill and showing the same coupled to an axle; Fig. 2, a vertical longitudinal section of the same on the line $\alpha\alpha$ of Fig. 1; Fig. 3, a cross-section on the line yy , looking in the direction of the arrows; Fig. 4, a detailed perspective view of a portion of the thill-iron, showing the knuckle and hooks thereon and the slot therein; and Fig. 5, a detailed perspective view of the key with the locking-lever attached thereto.

The axle A is provided with a clip B, which is attached thereto in the usual manner by nuts a , which are attached to the bolts b upon the lower ends of the clip and which project through a plate C upon the lower side of the axle. The clip B is provided with two forwardly-projecting lugs D, which may be

formed integrally with the clip or may be attached thereto in any suitable manner. The lugs D extend forwardly from the axle and are provided with a cross-bolt D' near their outer ends, which extends from one lug to the other and which may be formed in the same piece with the lugs or may be suitably attached thereto.

The thill E is provided with a thill-iron F, which is attached to the under side thereof in the usual manner, and which is bent at the point I and extends beyond the end of the thill.

The thill-iron F is provided with a raised knuckle d near the end of the thill, which extends across the upper surface of the thill-iron, with a slot e, which extends from said knuckle to the end of the thill-iron, and at the ends is turned up to form the hooks F' upon each side of the slot e.

The hooks F' are so shaped that they will fit nicely upon the cross-bolt D' and are of such a width that they will fit closely between the lugs D. The hooks F' are hooked upon the cross-bolt D' from the under side, and they will fit closely between the lugs D, which will prevent them from moving laterally. The hooks are held in this position by a key H, which is of the same width as the thill-iron F, and is provided with a depending tongue H', which fits closely into the slot e of the thill-iron F and is of the same thickness as the thill-iron, so that when the key is in position and the tongue H' is in the slot e the lower side of the tongue will be flush or nearly flush with the lower side of the thill-iron. The key H is also provided with a squared forward end, which fits closely against the knuckle d, a groove H² upon its rear end, which fits closely against the cross-bolt D', and upon its upper side with a rearwardly-extending tongue H³, which overlaps the cross-bolt D' and fits closely in the slot e between the hooks F' of the thill-iron, so that when the key is in position the hooks F' will be held closely upon the cross-bolt D', and the curve of the hooks upon one side of the bolt and the groove H² of the key upon the other side will form a socket around said bolt,

which will allow the shaft to swing freely thereon.

Pivotaly attached to the under side of the

key H by the screw-bolt f is a lever J, which at its upper end is of the same width as the tongue H', to which it is attached, to enable it to pass through the slot e of the thill-iron, and which 5 is provided with a flattened and elongated upper end J', so that by turning the lever to an angle with the slot e the part J' will extend across the slot and, resting against the lower side of the thill-iron F, will hold the key firmly 10 in position. The screw-bolt f is rigidly attached to the bottom of the key H and fits a thread in the top of the lever J, so that by turning the lever it may be tightened upon the key.

15 To attach the shaft to the axle, the hooks F' of the thill-iron F are hooked up over the cross-bolt D', the key H inserted between the bolt and the knuckle d, and the lever J turned to right angles with the thill-iron F, so that 20 the elongated end J' will extend across the slot e. To insert the key H, the lever J is first turned into line with the tongue H' and is inserted in the slot e of the thill-iron, and the key is then crowded into place. It will thus 25 be seen that by simply turning the lever J the coupling will be unlocked and the key may be easily removed and the coupling parts separated.

I have shown the coupling as applied to a 30 thill; but it is evident that it may be applied to a tongue as well.

Having thus fully described my invention, I claim as new and desire to secure by Letters Patent—

35 1. A thill-coupling consisting, essentially, of two forwardly-projecting lugs connected near the ends by a cross-bolt and suitably attached to the axle, a slotted thill-iron suitably attached to a thill, and having a raised 40 knuckle near the end of the thill, and having its slotted end formed into hooks adapted to engage said cross-bolt, and a key adapted to fit between said cross-bolt and the knuckle of the thill-iron, said key having a depending 45 tongue fitting the slot of the thill-iron and a rearwardly-extending tongue overlapping

said cross-bolt and entering the slot between the hooks of the thill-iron, and having suitable means for holding it in position, substantially as described. 50

2. A thill-coupling consisting, essentially, of two forwardly-projecting lugs suitably attached to the wagon-axle and connected near the outer ends by a cross-bolt, a slotted thill-iron suitably attached to a thill, having a raised knuckle near the end of the thill, and having its slotted end formed into hooks to engage said cross-bolt, and a key adapted to fit between said cross-bolt and the knuckle of the thill-iron, said key having a depending 60 tongue to fit the slot in the thill-iron and a rearwardly-extending tongue overlapping said cross-bolt and entering the slot between the hooks of the thill-iron, and having a lever attached to the lower side of said depending 65 tongue, which may be turned to extend across the under side of the thill-iron and lock the key, substantially as described. 70

3. In a thill-coupling, the combination, with the lugs D, having the bolt D' attached thereto, 75 and the thill-iron F, having the raised knuckle d, slot e, and terminal hook F', adapted to engage the bolt D' of the key H, adapted to fit between the bolt D' and knuckle d, having a depending tongue H' to fit the slot e of the 75 thill-iron, a rearwardly-extending tongue H³, to overlap the bolt D' and fit between the ends of the hooks F', and means, as depending 80 lever J, for locking it in position, substantially as described. 85

4. In a thill-coupling, the combination, with the key H, adapted to hold the thill-iron F and bolt D' together, as shown, and the thill-iron F, having the slot e, as described, of the lever J, pivotally attached to the under side of the key H and having an elongated flattened end J' to extend across the slot e and hold the key in position, substantially as described. 85
